Primary Examiner — Ian Simmons*Assistant Examiner* — Shannon Morgan(74) *Attorney, Agent, or Firm* — The Van Winkle Law Firm(57) **CLAIM**

The ornamental design for a bottle rack, as shown and described.

DESCRIPTION

FIG. 1 is a top perspective view of a bottle rack showing my new design;

FIG. 2 is a front elevational view thereof;

FIG. 3 is a side elevational view thereof;

FIG. 4 is a top plan view thereof;

FIG. 5 is a bottom plan view thereof; and,

FIG. 6 is a top perspective view thereof.

The broken lines in FIG. 6 of the bottle rack are for the purpose of illustrating environment, and form no part of the claimed design.

1 Claim, 6 Drawing Sheets(56)
